SIGNALING

James N. Whitaker, Weehawken, N. J., assignor to
Radio Corporation of America, a corporation of
Delaware

Application October 14, 1939, Serial No. 299,421

10 Claims. (Cl. 250—20)

This invention relates to a radio signaling system and particularly to the switching of a circuit from one signal to another, depending upon which signal is the stronger. More specifically, it relates to a vacuum tube and gas filled tube network wherein a means is provided for automatically switching from a standard or primary signal to an alternative or secondary signal at such times as the primary signal may be below a usable level, but only if the level of the secondary signal is of a usable value.

This invention, although especially useful in connection with the sub-carrier frequency modulation system described in the U. S. patent application of James E. Smith et al., Serial No. 270,332, filed April 27, 1939, is not restricted thereto.

In the above mentioned application Serial No. 270,332, the use of the switch was shown in block diagram form in Figure 2, and a schematic diagram of the switch was shown in Figure 5. The operation of the switch was described in the body of the specification. This switch was arranged to transfer the control of the system from the primary or fundamental input to the secondary or harmonic input at any time when the fundamental input was reduced in level to a predetermined value, and to again restore the control to the fundamental input when the level of said fundamental input was restored to its original usable level. This switching took place automatically and irrespective of the level of the signal in the secondary (or harmonic) channel.

Experience has proven that the energy present in the secondary (or harmonic) channel was not always of a usable value when the signal in the fundamental channel had dropped below the predetermined level. Therefore, when the switch transferred the control to the harmonic channel, the only signal present was often radio circuit noise, and the prime purpose of the switch (that of filling in a missing portion of the received intelligence) was defeated.

The purpose of the present invention is to improve the operation of the switch and to provide a differential operation in order that the switching may only take place after the fundamental signal has been reduced in amplitude below a predetermined level, and then only providing the signal in the harmonic channel is of a greater amplitude than the signal remaining in the fundamental channel.

Having thus described the purpose of the present invention, reference is made to the figure in the drawing and the following description.

Control lines 1 introduce the fundamental sig-

nal into the input 2 of amplifier tube 3. The circuit of this amplifier is conventional and will be understood from the drawing without further description. The output circuit 4 introduces the signal into full wave rectifier 5. The positive terminal 6 of this rectifier is connected to one end of resistance 7 and the center tap of transformer 4 (which represents the negative terminal of the rectifier system), is connected to the other end of the resistor. A smoothing condenser 8 is connected across these terminals.

Control lines 1a introduce the harmonic signal into the input 2a of amplifier tube 3a. The circuit of this amplifier, like that of amplifier 3 is conventional and merits no further description. The output circuit 4a introduces the signal into full wave rectifier 5a. The positive terminal 6a of this rectifier is connected to positive terminal 6 of the fundamental rectifier and therefore also to one end of resistance 7. The center tap of transformer 4a (which represents the negative terminal of this second rectifier system), is connected to one end of resistance 9. The other end of resistance 9 connects to one end of resistance 7. A smoothing condenser 8a is connected across resistor 9, and an adjustable tap on this resistor is grounded.

The elements thus far described constitute the differential arrangement used in connection with the electronic switch. This differential arrangement as shown in the drawing is set apart from the remainder of the switch by a dashed line to assist in the explanation, which covers the operation of the entire system.

The negative end of resistance 9 is connected through an appropriate resistor 10 to grid 11 of gas triode 12. The positive end of resistor 9 is connected through an appropriate negative grid biasing source 13 and grid resistor 14 to grid 15 of a similar gas triode 16. These gas triodes are also known as "thyatrons," "grid glow tubes," etc., and usually have a potential drop of approximately 15 volts across their anodes and cathodes when conducting. The anodes 19 and 20 of gas triodes 12 and 16 are connected together and to the positive terminal 41 of a suitable power source, of which the negative terminal is indicated as 42. Terminal 42 is also connected to ground. The cathodes 17 and 18 of the gas triodes are connected together through commutating condenser 21. Cathode 17 is also connected through resistance 22 to one end of resistance 23, which end is also connected to the cathodes of push-pull amplifier tubes 24 and 25. The other end of resistance 23 is grounded and

is connected to the center of the secondary of transformer 26, which is fed by input connection 27. The opposite ends of this transformer secondary are connected to the grids of tubes 24 and 25.

The anodes of tubes 24 and 25 are connected to the opposite ends of the primary winding of transformer 28. The center tap of this winding connects to cathode 18 of gas triode 12. Cathode 18 is also connected through resistance 29 to resistance 30 and to the cathodes of push-pull amplifier tubes 31 and 32. The opposite end of resistor 30 is connected to ground and also to the center of the secondary winding of transformer 33, which is fed by input lines 34. The opposite ends of the secondary of transformer 33 are connected to the grids of amplifier tubes 31 and 32. The anodes of these tubes are connected to the outside ends of the primary winding of transformer 35. The center tap of this winding is connected to cathode 17 of gas triode 16.

The secondary of transformer 35 is connected between the grid of amplifier tube 36 and ground. The secondary of transformer 28 is connected between the grid of amplifier tube 37 and ground. The anodes of tubes 36 and 37 connect to opposite ends of the primary winding of output transformer 38, the center tap of which is connected to positive terminal 41 of the power supply. The anodes of amplifiers 36 and 37 might also be connected in parallel and to one side of the primary winding of transformer 38, if desired. In that case, the opposite side of the winding would then be connected to terminal 41 of the power supply. The cathodes of these tubes are connected in parallel through biasing resistor 39 to ground. A by-pass condenser 40 is connected across resistor 39. The secondary of transformer 38 is connected to the utilization circuit which may be a limiter as shown in Figure 2 of Smith et al., application Serial No. 270,332, filed April 27, 1939.

The action of the complete differentially operated electronic switch is described as follows. Two separate operations are performed in the operation of the switch. First, the control of the switching by the two signals through a differential arrangement and, second, the actual transfer between two signals by means of the electronic switch proper. The two signals which are switched may be the same two signals that act differentially to operate the switch.

The differentiation between the two signals is a function independent of the operation of the switch. The operation of the switch, however, is dependent upon the differential between the two controlling signals. Therefore, it is found convenient and less confusing to first describe the action of the differential arrangement and then to describe the operation of the electronic switch, resulting from the differential currents derived from the two signals.

The action of the fundamental and harmonic signal amplifiers and rectifiers incorporating elements 1 to 6 and 1a to 6a inclusive and respectively is conventional and will be understood by reference to the circuit diagram without further description.

Let us assume for the moment that there is a fundamental signal input to 1. This signal is amplified and rectified and produces an IR drop across resistor 7. The end of 7 which connects to elements 6 and 6a of rectifiers 5 and 5a will be positive with respect to the opposite end of

this resistor. Let us say that the potential developed across resistor 7 by the fundamental signal is "X" volts. Let us also assume that a signal is also present at 1a of the harmonic channel. This harmonic signal will be amplified, but rectifier 5a cannot pass current unless the harmonic signal reaches a higher value than the fundamental signal. This is due to the biasing action on rectifier 5a due to the IR drop across resistor 7 caused by the fundamental signal. If the level of the fundamental signal is reduced, or if the signal level in the harmonic channel is increased so that the signal as rectified by 5a is greater than "X" volts, current will flow through resistors 9 and 7 from rectifier 5a. This current flow will cause a potential to appear across resistor 7 which will be greater than "X" volts and rectifier 5 will cease to pass signal currents for the same reason as previously described for rectifier 5a. Thus, it will be understood that the only rectifier which may pass current is the one receiving the stronger signal.

In actual practice the fundamental signal is always considerably stronger than the harmonic signal except under conditions where the R.-F. carrier fades out and permits the two sidebands to beat together and generate a strong second harmonic. For this reason it is apparent that rectifier 5a will operate only during these abnormal conditions.

The combined elements of the fundamental channel operate to produce an IR drop across resistor 7 only, and only acts to prevent the operation of rectifier 5a.

The elements of the harmonic channel operate to produce an IR drop across both resistors 7 and 9. Resistor 9 also forms a part of the electronic switch. Therefore, the signal applied to the harmonic channel not only acts to block the signal output of the fundamental channel, but also operates the electronic switch.

Having thus described the operation of the signal differentiating means, I will proceed to describe the action of the electronic switch with reference to the schematic diagram shown in the figure of the drawing.

We will again assume that the fundamental signal is usable; and rectifier 5a is blocked off by a drop of "X" volts across resistor 7. Grid bias 13 places a sufficient negative bias on the grid 15 of gas triode 16 to prevent conduction in this tube. No bias is applied to grid 11 of gas triode 12, which is now conducting. Current is flowing through this tube and resistors 29 and 30 to ground. The entire power supply voltage (minus the 15 volt tube drop) will now appear across these two resistors. Cathode 18 will be at a positive potential with respect to ground. Cathode 18 also connects to the center tap of transformer 28. By means of this connection, a positive potential is applied to the plates of amplifier tubes 24 and 25 through the transformer. The IR drop across resistor 23 due to the plate current of these amplifiers will provide a normal cathode bias for class A operation. Therefore, the fundamental (or doubled fundamental) signal will be amplified and passed on to the utilization circuit.

Let us now assume the second condition. The fundamental signal has been reduced until the IR drop across resistor 7 is substantially lower than "X" volts. Still no switching will take place unless there is a substantial input to the harmonic signal amplifier. As the input to the harmonic (or secondary signal) amplifier is in-

creased rectifier 5a will pass current through resistors 9 and 1. A negative bias is applied through resistor 10 to grid 11 of gas triode 12 because of the IR drop across resistor 9. Likewise, a positive potential will be applied to grid 15 of gas triode 16 through bias 13 and resistor 14. (This is due to the division of the potential appearing across resistor 9 by the variable tap, which is grounded.) As this positive potential is increased, bias 13 is overcome, and gas triode 16 begins to conduct. (This conduction is often spoken of as "firing." To say such a tube is "fired" means that the conduction is started.)

When gas triode 16 is fired, it raises the potential at the terminal of condenser 21 by the amount of drop across resistors 22 and 23. The potential of cathode 16 is momentarily raised above the potential of anode 20. The current through tube 12 is thus interrupted and the tube ceases to draw current, or is "extinguished." The time constant of condenser 21 is such that it cannot discharge sufficiently fast to lower the cathode to its operating voltage before de-ionization occurs in tube 12. Therefore, grid 11 resumes control. Since grid 11 is now made negative by the signal drop in resistance 9, tube 12 cannot restrike at this time after de-ionization takes place. Condenser 21 thereafter discharges through resistors 29 and 30 and recharges in the opposite direction.

When tube 16 was fired and tube 12 was extinguished, plate voltage was removed from amplifier tubes 24 and 25. Blocking bias was simultaneously removed from tubes 31 and 32. Blocking bias was also applied to tubes 24 and 25 due to the IR drop across resistor 23. Therefore, amplifiers 24 and 25 became inoperative. Likewise, amplifiers 31 and 32 became operative, and the harmonic or secondary signal was passed on to the output.

When the fundamental signal again returns to normal, or if the harmonic signal drops below a predetermined value, the bias on grid 11 of the tube 12 is reduced and this tube fires, and the opposite of the above action occurs, returning the switch to the first operating condition.

Although primarily intended for use in connection with sub-carrier frequency modulation systems, this invention should not be limited thereto.

For instance, any two signals may be switched by any other two signals. Additional elements may be added to provide a means for controlling the selection of any one of three or more signals from as many inputs, etc.

Also, it may be found desirable to use such a device to switch between two signals by a prearranged tone signaling device, such as, for instance, a time clock.

The system may also be adapted to double frequency keying wherein one signal of a given frequency would be transmitted for marking and another signal of a different frequency transmitted for spacing.

It may conceivably be used in a secrecy system where part of the elements of a letter were to be transmitted on one frequency and a part on the other.

I also do not wish to be limited to gas triodes, as any gas filled tube containing two or more elements could conceivably be used. This applies particularly to gas filled pentode tubes.

To obtain an overall picture of my present invention it may be restated briefly as follows:

As explained in the copending application of

James E. Smith et al., Serial No. 270,332, filed April 27, 1939, variable light impulses picked up by a scanning device are employed to produce corresponding electrical currents. These currents are employed to amplitude modulate an alternating current of constant frequency. The amplitude modulated currents are rectified and the rectified currents or waves are employed to frequency modulate a sub-carrier alternating current wave. This frequency modulated sub-carrier, which may be of an audible or super-audible frequency, in turn is employed to amplitude modulate a high frequency or radio frequency carrier wave. The carrier wave is transmitted to the receiver and picked up, as shown in the circuit diagram, by the receiving antenna RA.

The picked up waves are fed into a super-heterodyne receiver SHR whose output is the frequency modulated sub-carrier wave. In the event that the carrier wave fades, the super-heterodyne receiver will produce a second harmonic output effectively caused by the beating together of the sidebands received by the receiving antenna RA.

When the carrier is present and the super-heterodyne receiver reproduces in its output a strong fundamental frequency modulated sub-carrier, the filter FF passes the fundamental sub-carrier with its frequency modulations on to a limiter L and also, as explained previously, to the transformer 2 through line 1. The output of limiter L is fed through a low pass filter LPF, then to a frequency doubler FD, as explained in the copending application referred to, to transformer 26 through lines 27.

As explained, when the radio frequency carrier is strong and a strong fundamental sub-carrier is produced, this sub-carrier of doubled frequency as obtained from frequency doubler FD is fed through transformer 26, amplifiers 24 and 25 and amplifier 37 to the utilization or output circuit indicated at 38.

When the radio frequency carrier fades so that a strong second harmonic of the sub-carrier is produced in the output of the super-heterodyne receiver SHR, this harmonic energy passes by way of the band pass filter BPF to the harmonic transmission lines 1a. As explained hereinabove, with the strong second harmonic and a weak fundamental sub-carrier switching takes place so that the utilization circuit 38 is supplied with the harmonic energy through circuit 1a, conductors 34, transformer 33, amplifiers 31, 32 and amplifier 36.

It should be clearly understood that the frequency modulated sub-carrier at the transmitter shown in Figure 1 of the copending application of Smith, et al., referred to above, may be employed to frequency modulate the radio frequency carrier generated at the transmitter. In that event, the super-heterodyne receiver SHR should be of the type adapted to receive and translate the frequency modulated radio frequency waves into the frequency modulated sub-carrier. Also, if desired at the transmitter, the frequency modulated sub-carrier may be employed to phase modulate the radio frequency carrier, in which event the receiver SHR should be a phase modulation receiver. Also, if desired at the transmitter, the sub-carrier may be phase modulated and this phase modulated sub-carrier employed to phase modulate the radio frequency carrier wave, in which event, as before, the receiving system SHR should be a phase modulation receiver. Also, if a phase modulated sub-carrier is employed at the transmitter this phase modulated

sub-carrier may be employed to amplitude modulate the radio frequency carrier, in which event the receiver SHR should be a simple amplitude modulation receiver.

When the phase modulated sub-carrier is employed, the second harmonic of the phase modulated sub-carrier which appears in the output circuit at 38 may be translated by any suitable phase modulation translator. Thus, for example, the phase modulated sub-carrier may be fed to a detector through a filter which passes only one sideband of the doubled sub-carrier and the doubled carrier frequency of the sub-carrier. The detected output in this case would be a replica of the modulating envelope referred to hereinbefore.

Having thus described my invention, what I claim is:

1. A receiving system for receiving a carrier modulated by a sub-carrier comprising means for deriving from the modulated carrier sub-carrier wave energy, means for filtering out fundamental sub-carrier energy from the derived energy, additional means for filtering harmonic energy from the derived sub-carrier energy, means for raising the filtered fundamental energy to a harmonic frequency, and means including trigger-acting discharge tubes for selectively controlling the transfer of the raised energy or the directly derived harmonic frequency energy to a translating device, said selectively controlling means being adapted to favor one of said energies when both are of substantially equal value.

2. In a receiving system for a fundamental carrier wave containing a modulation frequency, means providing separate transfer paths for the fundamental carrier wave per se and for a harmonic component of said wave respectively, a translating device having an input circuit under alternative control of the energy in the two said paths, electronic switching means including gaseous discharge tubes for selecting the transfer path which is appropriate to the stronger of said fundamental and harmonic waves, and means controlled by the stronger of the two said waves for firing the proper gaseous discharge tube to cause the path selection.

3. In a receiving system the combination according to claim 2 and including means effective when one of said gaseous discharge tubes is fired for extinguishing the other of said tubes.

4. In a receiving system, the combination according to claim 2 and including a push-pull amplifier in each of said transfer paths, each of said amplifiers having a grid bias control circuit under the influence of the conductive and non-conductive states of said gaseous discharge tubes.

5. In a receiving system, the combination according to claim 2 and including a push-pull amplifier in each of said transfer paths, each of said amplifiers having an output circuit the source of anode potential for which is supplied through the space discharge path of one of said gaseous discharge tubes respectively.

6. The method of selecting one of two transfer circuits between a radio receiver and a translating device, by means of two alternatively conducting gaseous discharge tubes, which comprises separately rectifying a modulated sub-carrier wave component and a harmonic derivative of the side bands of the same sub-carrier wave, causing a first one of said tubes to be conductive so long as the amplitude of rectified energy from said sub-carrier wave component ex-

ceeds a predetermined value, causing a second one of said tubes to become conductive and the first said tube to be extinguished when the amplitude of said rectified energy falls below said predetermined value, and causing each said tube to control an appropriate one of said transfer circuits in such manner that only the stronger of the signals carried by said sub-carrier wave and its harmonic derivative respectively are passed to said translating device.

10 7. In a device for switching from one potential source to another, a utilization circuit, a first and a second gas tube, means whereby each tube at times starts to conduct and substantially

15 simultaneously quenches the other, a first and a second amplifier tube, each amplifier tube having its output circuit connected to said utilization circuit, the input circuit of one amplifier tube being connected to one of said potential sources and the input circuit of the other amplifier

20 tube being connected to the other of said potential sources, means for applying a positive potential to the plate of the first amplifier tube from the output circuit of the first gas tube while it is conducting, and means for applying a positive potential to the plate of the second amplifier tube from the output circuit of the second gas tube while it is conducting.

25 8. In a device for switching from one potential source to another, a utilization circuit, a first and a second gas tube, means whereby each tube at times starts to conduct and substantially

30 simultaneously quenches the other, a first and a second amplifier tube, each amplifier tube having its output circuit connected to said utilization circuit, the input circuit of one amplifier tube being connected to one of said potential sources and the input circuit of the other amplifier tube being connected to the other of said

35 potential sources, means for applying a positive potential to the plate of the first amplifier tube and a negative blocking potential to the grid of the second amplifier tube from the output circuit of the first gas tube while it is conducting, and means for applying a positive potential to the plate of the second amplifier tube and a negative blocking potential to the grid of the

40 first amplifier tube from the output circuit of the second gas tube while it is conducting.

45 9. In a device for switching from one potential source to another, a utilization circuit, a first and a second gas tube, means whereby each tube at times starts to conduct and substantially simultaneously quenches the other, a first and a second amplifier tube, each amplifier tube having its output circuit connected to said utilization circuit, the input circuit of one amplifier tube being connected to one of said potential sources and the input circuit of the other amplifier

50 tube being connected to the other of said potential sources, means for applying a positive potential to the plate of the first amplifier tube and a negative potential to the plate of the second amplifier tube from the output circuit of the first gas tube while it is conducting, and means for applying a positive potential to the plate of the second amplifier tube and a negative potential to the grid of the first amplifier tube from the output circuit of the second gas tube while it is conducting.

55 10. In a device for switching from one potential source to another, a utilization circuit, a first and a second gas tube, means whereby each tube at times starts to conduct and substantially

60 simultaneously quenches the other, a first and a second amplifier tube, each amplifier tube having its output circuit connected to said utilization circuit, the input circuit of one amplifier tube being connected to one of said potential sources and the input circuit of the other amplifier

65 tube being connected to the other of said potential sources, means for applying a positive potential to the plate of the first amplifier tube and a negative potential to the plate of the second amplifier tube from the output circuit of the first gas tube while it is conducting, and means for applying a positive potential to the plate of the second amplifier tube and a negative potential to the plate of the first amplifier tube from the output circuit of the second gas tube while it is conducting.

70 11. In a device for switching from one potential source to another, a utilization circuit, a first and a second gas tube, means whereby each tube at times starts to conduct and substantially

75 simultaneously quenches the other, a first and a second amplifier tube, each amplifier tube having its output circuit connected to said utilization circuit, the input circuit of one amplifier tube being connected to one of said potential sources and the input circuit of the other amplifier

second amplifier tube, each amplifier tube having its output circuit connected to said utilization circuit, the input circuit of one amplifier tube being connected to one of said potential sources and the input circuit of the other amplifier tube being connected to the other of said potential sources, means for applying a positive potential to the plate of the first amplifier tube and a negative potential to both the plate and

5 grid of the second amplifier tube from the output circuit of the first gas tube while it is conducting, and means for applying a positive potential to the plate of the second amplifier tube and a negative potential to both the plate and the grid of the first amplifier tube from the output circuit of the second gas tube while it is conducting.

JAMES N. WHITAKER.
